RECLINING CHAIR

Jay W. Campbell, Cambridge, Ohio

Application April 1, 1938, Serial No. 199,361

1 Claim. (Cl. 155—57)

My present invention relates to chair constructions and more especially to reclining chairs which are utilizable as such and also as conventional chairs.

5 Chairs which are capable of being used both as conventional chairs and as reclining chairs are now well known. While many advances have been made in the last few years in connection with such chairs, it has been found by experience 10 that there is still room for improvement. Prior chairs of this type have generally proved to have certain undesirable qualities. These include unnecessarily complicated structures, undesirably expensive structures, and structures which are 15 apt to wear rapidly or to develop looseness which partially destroys the utility of the chair.

One of the objects of my present invention is to produce a chair of the reclining type which is not only simple in construction and inexpensive to 20 manufacture, but which is unusually compact and sturdy in its make-up.

Another object of my invention resides in the production of a tiltable chair the tilting structure of which is in effect in a housing, thereby resulting in a chair of extremely long and trouble-free 25 life.

30 A further object resides in providing a stationary footed member for such a chair which has roller bearings countersunk therein and which therefore does not require the provision of special bearing surfaces; this stationary member cooperates with a specially shaped and concaved member attached to or forming part of the chair frame itself in contradistinction to general practice in 35 this art.

35 Other and further objects and advantages reside in the various combinations, sub-combinations, and details hereinafter described and claimed and which will be either understood by those skilled in this art or pointed out hereinafter.

40 In the accompanying drawing wherein I have illustrated a preferred embodiment of my present invention:

Figure 1 is a fragmentary perspective view of a 45 chair embodying the present invention;

Fig. 2 is a side elevational view of the parts of Fig. 1 without the housing face plate and showing the tilted position of certain of the parts in dotted lines;

50 Fig. 3 is a bottom view of the structure of Figs. 1 and 2; and

Fig. 4 is a fragmentary perspective view of the stationary member.

The construction of chairs of the upholstered, 55 overstuffed or club type is well known and needs

no detailed description here. Such will be found, for example, in my co-pending application Serial No. 177,486, filed December 1, 1937. Such chairs include a conventional side rail 10 on each side of the chair. The opposite side rails are connected 5 by front rail 11 and rear rail 12 in usual manner to the seat framework of the chair. Each side rail 10 has a rear post 13 rising therefrom, from which the back of the chair is formed. Each side rail 10 also has at its forward end a suitable foot 10 14, and a reinforcing block or piece 15 is generally employed at the intersection of the side rail and the front rail for the usual purposes.

My invention comprises the addition of certain structure to provide a tiltable chair. Secured to 15 each side rail 10 on the inner surface thereof is a plano-concave shaped member 16 which is suitably secured to the side rail at points 17 by any desired instrumentalities. This member 16 is integral with the chair and moves therewith when 20 the same is tilted. The concave under-side of such member 16 is appropriately contoured in order to provide a continuous bearing surface 18 which has a steeper slope at the front thereof than at the rear, this arrangement providing new 25 and unusual qualities in connection with the operation of the chair, giving the capacity to respond quickly and instantly to the desires of the occupant of the chair, while, at the same time, reducing the total amount of energy required on the 30 part of the occupant in order to reach the desired tilted position. Such an arrangement also causes the end (maximum tilted) position to be approached relatively slowly and, hence, more safely, and, therefore, the change in position becomes 35 more pleasing and satisfactory to the chair occupant than if the reverse were true as in certain prior constructions.

Operatively associated with each such shaped member 16 is a stationary foot member 19. This 40 member has an upper surface or edge 20 which is slightly convex and which is generally complementary to the concave under-surface 18 of shaped member 16. At the points designated by the numerals 21, the stationary base member is 45 partially cut away to form a pair of spaced recesses, and each such recess is less in its transverse dimension than the width of the stationary base member so as to produce two generally semi-circular ribs or flanges 22. Each such rib or 50 flange is provided with a cut-out portion 23 disposed in alignment with each other.

Disposed in each such recess 21 in each such stationary foot member 19 is a transverse bearing support 24 which is preferably in the form of 55

a short section of pipe or solid rod. The external diameter of each pipe or rod 24 is substantially equal to the internal length of each cut-out portion 23 and the pipe or rod preferably projects 5 slightly above the upper edge of each rib or flange 22. Such pipe or rod 24 may be suitably secured in place by any desired fastening instrumentality, for which purpose the rod or pipe may be transversely apertured or bored to provide a passage for a spike, screw, or the like 25. Rotatively mounted on each such pipe or rod 24 is a cylindrical bearing member 26 which is adapted to roll on the continuous bearing surface 18 formed on the under-side of the shaped 10 member 16 in response to occupant-controlled positioning of the chair.

Disposed on the concave under surface 27 of each stationary foot member 19 is a triangularly shaped block or stop member 28 which has the 20 configuration shown in Figs. 2 and 3. This member is secured to the stationary foot member 19 by suitable screws or the like 29 which hold it firmly in place. The forward portion of the triangularly shaped member has a short sloping 25 portion 30 such as to act as a wedge in conjunction with the transverse limiting member 31 which is connected between side rail 10 and face plate 32 in such manner that it does not interfere in any way with tilting movement of the 30 chair but acts to limit relative tilting movement of the chair with respect to the foot member 19 in both directions. Rearward tilting of the chair is limited by contact between transverse stop member 31 and the wedge-like portion 30 of the 35 block member 28. When the chair is in its normal, upright position, the transverse stop member 31 comes into contact with the under surface of the stationary foot member 19 (see Fig. 2) in such manner as to give the chair, when in this 40 position, substantially the rigidity, strength and immovability found in non-tilting chairs. Thus, at all times, a safe chair is provided which, when it is desired to be used as a tilting chair, can be tilted backwardly but not to such an extent as 45 would be likely to cause the chair to overturn. Thus, within the limits of the tilting movement, the chair may be occupied and used with complete safety; and yet this is brought about in an

extremely simple and desirable manner not shared by prior constructions.

The structure is completed by the face plate 32 already referred to which is secured to the shaped member 16 by means of screws 33 or in any other 5 suitable manner.

It will thus be apparent that I have provided a chair which is capable of being tilted by the occupant thereof and which is not only extremely simple and inexpensive in its construction but 10 which gives a new quality of utility and service in connection with chairs of this type. Due to the arrangement shown the number of members utilized is maintained at a minimum, thus lessening 15 chances for breakage or maladjustment and, at the same time, practically eliminating the necessity for ever making repairs but which, if required, can be made with a minimum of trouble. The provision of a housing, in effect, for the reclining construction is, I believe, new and highly 20 advantageous.

The above is presented as illustrative rather than limitative, and I may make suitable additions, omissions, variations and substitutions without departing from the spirit and principles 25 hereof, and all such are deemed to be a part of this invention. Rather the invention is to be defined by the subjoined claim.

Having thus described my invention, what I claim as new and desire to secure by Letters Patent is:

In a chair of the kind described, a side rail, a shaped member secured to said side rail and having an under concave bearing surface, a face plate substantially co-extensive with and secured 35 to said shaped member and a stationary base member operatively associated with said shaped member, said base member having roller bearings mounted in its upper edge adapted to roll on the bearing surface of said shaped member 40 and a wedgelike member secured on the under side of such base member whereby to limit tilting movement of such chair with respect to such base in cooperation with a transverse stop member provided and extending between said face 45 plate and said side rail.

JAY W. CAMPBELL.
